985,002. SHELF ATTACHMENT FOR
TENTS. WILLIAM CAREY BROWN, U. S.
Army. Filed Oct. 28, 1910. Serial No.
589,555.

To all whom it may concern:

Be it known that I, WILLIAM CAREY BROWN, a citizen of the United States, and a major in the U. S. Army, stationed at Washington, in the District of Columbia, have invented an Improved Shelf Attachment for Tents, of which the following is a specification.

My invention is embodied in a useful and inexpensive shelf-like attachment for tents of rectangular plan with a wall, such as wall tents, common tents, and hospital tents used in the United States Army, the same serving as a supporter or holder for various articles used by the occupants of the tent. The shelf is made of duck or other stout fabric and in approximately triangular shape, the two sides being vertical and tapered longitudinally and the whole being detachably secured to a tent in one of the angles of the wall, preferably by means of the lines or cords with which such tents are commonly provided for the purpose of supporting the sides when rolled up to admit air or sunlight. The shelf occupies small space which is ordinarily not required for other purposes, and is foldable with the tent, although it may be easily and quickly detached when desired.

The details of construction, arrangement, and attachment of the shelf are as herein-after described, and illustrated in the accompanying drawing, in which—

Figure 1 is a sectional perspective view of a wall tent with my improved shelf attachment secured and arranged as in use. Fig. 2 is a sectional view on the line 2—2 of Fig. 3. Fig. 3 is a top view of a portion of an angle of a wall tent with my improved shelf secured thereto. Fig. 4 is a perspective view of the shelf. Fig. 5 is a plan view of the three pieces of fabric of which the shelf is formed.

The shelf is made of stout fabric, preferably duck of good quality and at least medium thickness. It is constructed in angular, preferably triangular, form, and composed of vertical divergent sides 1 and a bottom 2 which may be said to constitute the shelf proper. The sides 1 are triangular or tapered from one end to the other—see especially Fig. 5—and the broader or base ends are juxtaposed and united by sewing or otherwise, while the triangular bottom 2 is secured to, and extends between, the lower edges of the sides 1. Since such lower edges are inclined from the inner or base end upward, it results that when the shelf is duly adjusted and attached in a tent angle as shown in Fig. 1, the upper edges of the sides being then horizontal, the bottom 2 is held inclined from the extended front edge downward to the apex of the triangle. Thus the shelf is deep at its inner end and shallow at its outer end.

The angle or inclination of the bottom 2 is important practically, since it makes the shelf a secure holder for various small articles which may be laid upon it, or, in other words, prevents the articles from sliding forward and falling off the edge of the shelf.

The shelf is attached to the tent wall 3 in the angle of the same and at the upper edge of the wall by means of ropes or cords attached to the tent; and for this purpose I employ the lines 4 with which wall tents are ordinarily provided for use in supporting the sides of the tent when rolled up. Such lines are passed through the tent from inside to outside at the seams, being secured to the tent wall, and when not in use hang free on both sides of the wall. My improved shelf is provided with an eye, preferably a grommet 5, at its inner upper angle and also at its outer angles. Through these eyes or grommets 5, the aforesaid lines 4 that hang on the inner side of the tent wall 3 are passed and then knotted or tied, whereby the shelf is held securely but detachably in place, with its bottom inclined as before stated and as shown in the drawing.

The lines 4 constitute a convenient means for securing the shelf detachably, so that it is unnecessary to provide supplemental ties or fastenings for the purpose, while the lines are still left free to perform their ordinary function of supporting the rolled up side of the wall of the tent when required.

What I claim is:—

1. A tent attachment consisting of a foldable shelf-like holder for various articles, constructed of stout fabric and having vertical sides united at their inner ends and tapered therefrom to their outer ends, and the bottom of the shelf proper secured to and extending between the inclined lower edges of such sides, whereby the bottom of the shelf is lower at its inner than its outer end, substantially as described.

2. A tent attachment consisting of a foldable shelf-like holder for various articles, constructed of stout fabric and formed of three pieces of the same, such pieces comprising triangular sides whose lower edges are inclined from the base upward, and a triangular bottom piece which is united to the lower inclined edges of the side portions, the latter being also united at the inner angle, as shown and described.

3. The combination, with a tent having lines secured adjacent to the upper edge of its wall, of a foldable shelf constructed of stout fabric, the sides being tapered to their outer ends and the bottom or shelf proper being united to and extending between the inclined lower edges of the sides, the shelf being adapted at its angles for engagement with the aforesaid ties, as shown and described.

WILLIAM CAREY BROWN.
